LOCK MECHANISM

Edward N. Jacobi, Milwaukee, Wis., assignor to
 Briggs & Stratton Corporation, Milwaukee,
 Wis., a corporation of Delaware

Application June 20, 1949, Serial No. 100,258

14 Claims. (Cl. 70—362)

1

This invention relates to locks and refers more particularly to locks of the type commonly known as pillar locks which are especially adapted for use with automobile door handles and the like.

In locks of this type the lock assembly is located in the door handle and comprises a rotary cylinder mounted in a sleeve-like casing and having an operating shaft projecting from its rear to transmit rotation of the cylinder to latch mechanism on the door to be actuated. The door handle has an elongated tubular stem on its inner end to receive the operating shaft and the bore of the stem opens to the front of the handle through a counterbore in which the lock cylinder and casing are received.

Ordinarily the lock casing is fixed in the door handle, and in locks of the type here in question a torsion spring is connected with the lock cylinder to exert sufficient torsional force thereon to snap the same to its locked position of rotation.

In the interests of compactness it is desirable to make the sleeve-like casing for the lock cylinder with as thin a wall as possible. However, whenever a thin walled casing is employed, the cooperating rotation stops on the cylinder and the casing must be made relatively small with the result that the torsion spring, in snapping the lock cylinder to its locked position of rotation defined by the stops, causes them to wear rapidly.

Accordingly it is one of the objects of this invention to provide lock mechanism of the character described with a casing formed from a thin walled sleeve and to provide rotation stops which will easily withstand the hammering effect to which they are subjected by the torsion spring of the lock.

More specifically it is an object of this invention to provide a lock mechanism of the character described wherein the cylinder and casing have one set of cooperating rotation stops located adjacent to the front of the lock cylinder and are provided with a set of auxiliary rotation stops adjacent to the rear of the lock cylinder.

Still another object of this invention resides in the provision of a lock mechanism of the character described with cooperating brake parts on the cylinder and lock casing which are brought into engagement as the lock cylinder approaches its locked position for the purpose of slowing the rotation of the lock cylinder under the influence of the torsion spring to thus relieve the shock of engagement between the rotation stops.

More specifically, it is another object of this invention to provide lock mechanism of the character described with a torsion spring to return

2

the lock cylinder to its locked position of rotation, and wherein a projection on the inner end of the cylinder is caused to ride up an inclined ramp formed on the lock casing as the cylinder approaches its locked position of rotation under the influence of the torsion spring to effect a braking action slowing cylinder rotation and relieving the shock of engagement between the rotation stops of the cylinder.

10 A further object of this invention resides in the provision of a lock mechanism of the character described wherein the braking action taking place slightly before engagement of the rotation stops of the cylinder produces relative endwise motion between the cylinder and its casing, and wherein such motion is yieldingly resisted by a recoil spring which tends to increase the effectiveness of the brake by which rotation of the cylinder is slowed.

15 In pillar locks of the type to which this invention pertains it is also customary to provide a detachable driving connection between the lock cylinder and the operating shaft which prevents endwise separation of the shaft from the cylinder except upon tilting of the shaft to a predetermined position at an angle with respect to the axis of the cylinder. Such a detachable connection is shown in Patent No. 2,004,435, issued June 11, 1935, to Edward N. Jacobi. In this 20 patent, however, the driving connection between the operating shaft and the lock cylinder must be established before insertion of the lock cylinder into its casing, the casing holding the operating shaft against detachment when in position encircling the cylinder.

25 The present invention likewise provides a readily detachable driving connection, of the type described, between the operating shaft and the inner end of the lock cylinder, and it is a further object of the invention to so arrange the lock parts that the shaft cooperates with the cylinder to hold the casing assembled thereon while permitting detachment of the operating shaft from the cylinder upon rotation of the cylinder to a predetermined position relative to the casing.

30 Still another object of this invention resides in the provision of a lock mechanism of the character described wherein cooperating parts on the cylinder and its casing maintain the torsion spring, by which the cylinder is returned to its locked position, out of frictional contact with respect to the casing so as to minimize loss of torque which normally results from rubbing engagement between the torsion spring and the lock casing.

35 With the above and other objects in view

which will appear as the description proceeds, this invention resides in the novel construction, combination and arrangement of parts substantially as hereinafter described, and more particularly defined by the appended claims, it being understood that such changes in the precise embodiment of the herein disclosed invention may be made as come within the scope of the claims.

The accompanying drawings illustrate one complete example of the physical embodiment of the invention constructed in accordance with the best mode so far devised for the practical application of the principles thereof, and in which:

Figure 1 is a view partly in side elevation and partly in longitudinal section and showing the lock mechanism of this invention in place in a door handle and in its locked position;

Figure 2 is a longitudinal sectional view taken through Figure 1 along the plane of the line 2—2;

Figure 3 is a cross sectional view taken through Figure 1 along the plane of the line 3—3, with the lock mechanism removed from the door handle;

Figure 4 is a view similar to Figure 3 but showing the lock cylinder rotated to the position at which detachment of the operating shaft is possible;

Figure 5 is a fragmentary detail view partly in longitudinal section and partly in side elevation illustrating the manner in which attachment and detachment of the operating shaft is effected;

Figure 6 is a group perspective view of the lock cylinder and the casing therefor along with the torsion spring by which the cylinder is yieldingly maintained in its locked position of rotation;

Figure 7 is a view similar to Figure 1 but illustrating the lock cylinder rotated to a position at which the rotation arresting brake is about to become effective; and

Figure 8 is a cross sectional view taken through Figure 7 along the plane of the line 8—8 and illustrating the pilot means which insures that the full force of the torsion spring will be employed to return the cylinder to its locked position of rotation.

Referring now more particularly to the accompanying drawings in which like numerals designate like parts throughout the several views, the numeral 5 represents the sleeve-like casing for the lock mechanism, and the numeral 6 designates the lock cylinder which is rotatably received within the front portion 7 of the casing. The front portion 7 of the casing has a relatively thin wall, and has a rearward extension 8 of slightly less diameter joined thereto and projecting rearwardly beyond the inner end of the lock cylinder.

At its forward end the lock cylinder has an enlarged head 9 of approximately the same diameter as the exterior of the sleeve 7, and a series of arcuate shoulders 10 extending about the circumference of the cylinder immediately behind the enlarged head 9 thereof are adapted to be engaged by the front edge 11 of the casing to define the forward limit of the casing on the cylinder.

A locking member of the side bar type, not shown, normally projects into a longitudinal slot 12 in the side of the sleeve 7 to lock the cylinder against rotation relative to the casing, and this locking member is retractable in a conventional manner by the insertion of a suitable key 13 into the lock cylinder from the front thereof to free the cylinder for rotation inside the casing.

The inner end of the cylinder has a reduced portion 15 thereon and a pilot 16 at its extremity smaller in diameter than the reduced portion 15. These parts have an axial hole 17 therein into which the forward end of the operating shaft 18 is received to be drivingly connected with the cylinder in a manner similar to that illustrated and described in the aforementioned Patent No. 2,004,435.

Briefly, the driving connection between the forward end of the operating shaft and the lock cylinder comprises a hook-like portion 20 on the shaft which is engaged behind a shoulder 21 projecting inwardly into the hole 17 from the side wall of the extension 15 and pilot 16. The driving connection here illustrated, however, differs from that of the afore-mentioned patent in that the shaft has a splined connection with the lock cylinder established by the engagement of a longitudinally projecting fin 22 on the forward extremity of the shaft in a longitudinal slot 23 in the wall of the pilot and opening to the extreme rear of the pilot. The slot 23 is substantially diametrically opposite the shoulder 21 behind which the hook-like forward extremity 20 of the operating shaft engages. The driving connection between the shaft and the lock cylinder, of course, may be readily established or disconnected upon tilting the shaft to a predetermined angular position with respect to the axis of the cylinder, as shown in Figure 5.

As will be apparent from a consideration of Figure 2, it will be seen that the connection between the operating shaft and the lock cylinder affords a degree of relative endwise motion between these parts without impairing the effectiveness of the driving connection between them. Some degree of endplay in the cylinder-to-shaft connection is desirable, however, as it assures ease of assembly and detachment of the operating shaft.

The portion 25 of the operating shaft which lies immediately to the rear of the lock cylinder 45 and is encircled by the sleeve extension 8 is reduced in diameter to provide a shoulder 26 facing the rear end of the sleeve extension to prevent rearward sliding of the lock casing off of the cylinder. For this purpose, when the parts are held in coaxial relationship as shown, the shoulder 26 on the operating shaft is adapted to be engaged by diametrically opposite abutments 27 and 28 at the rear of the sleeve extension 8. These abutments extend radially inwardly from the wall of the sleeve extension and while the abutment 27 is solid, as seen in Figure 3, the abutment 28 has the central portion thereof removed.

The arrangement of the abutments 27 and 28 is such that they will present surfaces at the inner end of the sleeve extension which will engage with the shoulder 26 on the operating shaft even though the shaft may be tilted at a slight angle to the axis of the lock cylinder prior to assembly of the lock mechanism in the door handle 30. Hence, the casing is maintained assembled on the lock cylinder through the cooperation of the shoulders 10 at the front of the cylinder with the shoulder 26 on the operating shaft so as to facilitate handling of the lock mechanism prior to its installation. It is important to note, however, that the shoulders 10 and 26 permit limited longitudinal sliding motion of the casing relative to the cylinder for a purpose to be described shortly.

With this manner of holding the casing on the lock cylinder, it is necessary that the shaft be connected with the cylinder after insertion of the cylinder into the casing 5. This can be effected in only one position of rotation of the cylinder relative to the casing, which position is shown in Figures 4 and 5.

As here illustrated the lock cylinder is rotated approximately halfway between its locked and unlocked positions to bring the cylinder to an intermediate station at which the operating shaft may be tilted upwardly between the opposite abutments 27 and 28 on the sleeve extension and into a notch 32 cut into the rear extremity of the extension. This notch enables the shaft to be tilted far enough to disengage its hooked end 20 from behind the shoulder 21 on the inner end of the lock cylinder.

It will be apparent, therefore, that insertion of the operating shaft through the open rear of the casing and into the axial hole 17 in the inner end of the cylinder with the parts in their positions shown in Figure 5 automatically locks the parts in their assembled relationship.

In locks of the type herein concerned, the lock cylinder is adapted to be returned with a snap to its locked position after actuation thereof, by means of a torsion spring 34. In the present instance the torsion spring is received inside the sleeve extension 8 on the lock casing and encircles the pilot 16 projecting rearwardly from the inner end of the lock cylinder as well as a cooperating pilot 35 on the sleeve extension projecting forwardly toward the rear end of the lock cylinder. The diameter of the torsion spring is such that its convolutions substantially closely encircle the coaxial pilots 16 and 35; and its length is such that it is received in the space between the rear end 15' of the reduced portion 15 on the lock cylinder and a step 36 on the inside of the sleeve extension without any compression of the spring.

End hooks 37 and 38 are bent from the front and rear convolutions of the spring to provide for connection of the spring with the cylinder and its casing. For this purpose the reduced portion 15 of the cylinder is provided with a longitudinal slot 39 in its side leading forwardly from the surface 15' against which the front of the torsion spring abuts to receive the forwardly projecting hook 37 on the spring; while the sleeve extension is provided with an aperture 40 leading longitudinally rearwardly through the step 36 at the rear of the extension in line with the central cutaway portion of the abutment 28 to receive the rear hook 38 on the spring.

Obviously the angular relationship between the slot 39 and the aperture 40 must be such that the spring is wound up slightly in the locked position of the cylinder shown in Figures 1, 2 and 3, so that the spring yieldingly resists rotation of the cylinder out of its locked position and is enabled to exert sufficient torsional force on the cylinder to rotate the same rapidly to its locked position following actuation of the lock mechanism.

It is important to note that the diameter of the torsion spring is so related to the diameter of the pilots 16 and 35 that the distortion of the end convolutions of the spring resulting from rotation of the lock cylinder toward unlocked position against the force of the spring cannot throw the spring into rubbing contact with the inner wall of the sleeve extension. This is brought about by the engagement of the end convolutions

with the exterior of the pilots approximately 90 degrees away from the end hooks of the spring. Attention is also directed to the fact that such engagement between the spring and the pilots is confined to the end convolutions of the spring. The intermediate convolutions cannot come into rubbing engagement with the surfaces of the pilots, which surfaces converge toward their adjacent ends and are thus somewhat conical.

Distortion of the torsion spring which might tend to throw it against the inner wall of the sleeve extension during rotation of the lock cylinder against the action of the spring is also largely minimized by having the end hooks 37 and 38 not only bent slightly radially inwardly but by having them also extend at an angle less than 90 degrees to their respective convolutions, as shown best in Figure 6. When so disposed, the end hooks also preclude such camming action which might tend to compress the spring upon rotation of the cylinder toward unlocked position, and which would cause rubbing together of the spring convolutions and consequently interfere with rotation of the cylinder.

Compression of the spring and consequent rubbing of its convolutions against one another and against the inner wall of the sleeve extension as well as the pilots is thus effectively eliminated; and the full force of the spring is made available to return the lock cylinder to its locked position of rotation with a strong and positive snap action.

Because of the tendency of the torsion spring to return the cylinder to its locked position with a snap action the rotation stops of the cylinder are subjected to unusual hammering; and this invention provides novel rotation stops on the cylinder and casing which are capable of withstanding such hammering. One set of cylinder carried stops is provided by a pair of circumferentially spaced projections 41 and 42 on the exterior of the lock cylinder immediately behind the shoulders 10. These stops engage in a relatively shallow arcuate recess 43 in the bore of the casing opening to the front edge 11 thereof. The ends 44 and 45 of the recess provide casing carried stop abutments which cooperate with the projections 41 and 42, respectively, to define the locked and unlocked positions of cylinder rotation.

Both the cylinder carried projections and the casing stops, however, are necessarily relatively small because of the thin wall on the casing, and are alone incapable of long withstanding the substantial force with which they are brought into engagement by the torsion spring. For this purpose auxiliary stops are provided at the rear of the lock cylinder.

These auxiliary stops comprise a strong tongue-like rearward projection 46 on the pilot 16, and cooperating stops 47 and 48 on the pilot 35. The pilot stops are formed by cutting away a front portion of the wall thereof to receive the tongue 46 on the cylinder, and so that the circumferential termini of the cutaway portion which provide the stops 47 and 48 lie in the path of rotation of the tongue 46.

Obviously tongue 46 engages its stop 47 simultaneously with engagement of the projection 41 with its abutments 44 at the front of the casing to relieve the latter of wear and the hammering effect produced by return of the cylinder to locked position under the influence of the torsion spring. Likewise, the projection 46 is adapted to engage the stop 48 on the casing pilot simultaneously

with engagement of the projection 42 with the remaining stop 45 at the front of the casing to define the unlocked position of the cylinder.

The manner of mounting the lock mechanism in the door handle and of retaining the mechanism therein is also novel. The handle has a main counterbore 50 in its front to receive the lock mechanism, and the operating shaft 18 projects rearwardly through the bore 51 of a tubular stem 52 on the inner end of the handle. The counterbore 50 freely accommodates the front of the lock mechanism, and has a slightly reduced diameter near the stem 52 to rotatably and slidably receive the reduced casing extension 8.

The entire lock mechanism is readily secured in the handle by means of a tangent pin 53 in the stem 52 received in an annular groove 54 in the operating shaft, as seen best in Figures 1 and 2. The pin 53, in holding the shaft against longitudinal displacement, thus also maintains the cylinder against forward displacement from the bore in the handle through the driving connection between the shaft and cylinder. Also, as described previously, the casing is held against longitudinal displacement through the cooperation of the shoulders 10 at the front of the lock cylinder and the shoulder 26 on the operating shaft adjacent to the rear of the casing.

However, the entire lock mechanism is yieldingly urged forwardly to take up any clearance in the pin connection to the operating shaft and the slack in the driving connection between the shaft and lock cylinder, by means of a compression spring 56 seated in the bottom of the reduced portion of the counterbore and bearing against the rear end of the casing extension 8. This spring forces the casing forwardly, and through engagement between the casing and the lock cylinder, also serves to push the cylinder forwardly. This draws the operating shaft forwardly along with the cylinder so as to engage the rearmost side wall of the annular groove 54 with the tangent pin 53, thus holding all of the parts of the lock mechanism against rattling.

According to this invention the spring 56 also serves as a recoil element to cushion the shock incidental to engagement of the rotation stops under the influence of the torsion spring 34. In this respect the compression spring cooperates with a brake which is defined conjointly by the outer extremity of the stop projection 46 on the rear of the lock cylinder and an inclined ramp 58 on the casing carried pilot just ahead of the stop 47 which defines the locked position of the cylinder.

Referring to Figure 7, it will be observed that the stop projection 46 is about to be engaged with the inclined ramp 58 by further rotation of the lock cylinder toward the stop 47 on the casing pilot, and it will be seen that the incline of the ramp 58 is such as to tend to effect forward displacement of the lock cylinder with respect to the handle. Such forward motion of the lock cylinder, of course, is precluded by its connection with the operating shaft 18, and hence the camming effect produced by the stop projection riding up the inclined ramp is manifested in a rearward sliding motion of the casing against the compression spring 56.

Hence it will be seen that the spring 56 not only absorbs some of the shock incidental to return of the cylinder to its locked position, but it also effects good frictional engagement between the cooperating surfaces on the stop projection 46 and the ramp 58 to produce a braking

action immediately in advance of engagement between the rotation stops at the locked position of cylinder rotation. This brake materially slows down the rotation of the cylinder and consequently lessens the hammering effect on the rotation stops which ordinarily would result from their engagement under the influence of the torsion spring.

As noted previously, the lock cylinder is shown in its locked position of rotation in Figures 1 and 2, and it will be noted that the stop projection 46, while engaged with its cooperating stop 47 on the casing pilot has ridden up the ramp 58 and forced the casing 5 rearwardly against the compression spring 56 so as to effect a slight separation between the front of the casing and the shoulders 10 at the front of the lock cylinder.

From the description thus far it will be apparent that the casing must be free to slide forwardly and rearwardly in the counterbore of the handle, but it will also be realized that the casing must be restrained against rotation in the handle so that the lock cylinder may be rotated between its locked and unlocked positions relative to the casing.

This manner of connecting the casing to the lock handle may be accomplished by any suitable splined connection therebetween, but in the present instance the connection is afforded by engagement of the lugs 27 and 28 at the rear of the casing extension in diametrically opposite notches 60 formed in the front end of a hub 61 on the lock handle projecting axially forwardly from the bottom of the reduced portion of the counterbore and passing inside the compression spring 56 into the rear of the casing extension 8. Both the lugs 27 and 28 as well as the notches 60 have sufficient longitudinal length as to accommodate the recoil motion of the casing without disengagement of the lugs from the notches 60.

From the foregoing description taken in connection with the accompanying drawings it will be readily apparent to those skilled in the art that this invention provides an improved lock mechanism for door handles featuring a novel manner of holding the parts of the mechanism assembled prior to installation in the handle; and of providing for protection of the rotation stops through the brake action which is effected immediately prior to engagement of the stops defining the locked position of cylinder rotation. A further highly desirable feature afforded by the lock mechanism of this invention is the assurance against loss of torque in friction which frequently occurs in locks of this type employing a torsion spring to forcefully return the lock cylinder to its locked position of rotation.

In addition, this invention also materially simplifies the installation of the lock mechanism in its mounting member or handle, the whole mechanism being retained in the handle by a single pin passing through the handle stem and into a groove in the operating shaft.

What I claim as my invention is:

1. In a lock of the character described: a casing comprising a thin-walled sleeve having an arcuate recess in its bore at the front end of the sleeve to define an internal stop at one end of said recess; a lock cylinder rotatable in said sleeve; a stop abutment on the side of the cylinder projecting into said recess in the sleeve and engageable with said stop thereof to define the locked position of rotation of the cylinder; a rearward extension on the sleeve; a torsion spring inside said sleeve extension and connected with

the cylinder and extension to bias the cylinder to its locked position of rotation; and cooperating auxiliary stops on the cylinder and sleeve extension engageable simultaneously with engagement of said first designated stops to relieve the same of shock incidental to spring propelled rotation of the cylinder to its locked position.

2. In a lock of the character described: a sleeve-like casing having a recess in the front thereof to define at least one internal stop; a lock cylinder rotatable in said casing; a stop abutment on the side of the cylinder projecting into said recess in the casing and engageable with the stop provided by said recess to define the locked position of rotation of the cylinder; a rearward extension on the casing projecting beyond the rear of the lock cylinder; a shoulder in the interior of said casing extension spaced from the rear of the lock cylinder; a torsion spring inside the casing extension and confined between the rear of the cylinder and said shoulder on the casing extension; connections between said torsion spring and the cylinder and casing extension whereby the spring biases the cylinder to its locked position of rotation; pilot means encircled by said torsion spring including a rearward projection on the lock cylinder and a cooperating forward projection on the casing extension; and cooperating auxiliary stops on said pilot means engageable simultaneously with engagement of said first designated stops to relieve the same of shock incidental to spring propelled rotation of the cylinder to its locked position.

3. In a lock of the character described: a casing; a lock cylinder rotatable in the casing between locked and unlocked positions; a spring reacting between the casing and the cylinder and exerting a torsional force on the cylinder capable of rotating the same to its locked position; cooperating stops on the cylinder and casing adjacent to opposite ends of the cylinder for defining said locked position of the cylinder; and cooperating means on the cylinder and the casing, including one of said stops, frictionally engageable during spring propelled rotation of the cylinder to its locked position to provide a brake for slowing down the rotation of the cylinder prior to engagement of said stops.

4. In a lock of the character described: a casing; a lock cylinder rotatable in the casing between locked and unlocked positions; a spring reacting between the cylinder and the casing and exerting a torsional force on the cylinder sufficient to effect rotation thereof toward locked position with a snap action; cooperating stops on the cylinder and casing defining the locked position of cylinder rotation; and cooperating parts on the cylinder and the casing frictionally engageable with each other during spring propelled rotation of the cylinder to its locked position to provide a brake for slowing the rotation of the cylinder prior to engagement of said stops.

5. The lock set forth in claim 4 wherein said casing comprises a thin-walled sleeve having an arcuate recess in its bore, one end of which provides an internal stop engageable by a projection on the side of the cylinder extending into said recess to define the locked position of rotation of the cylinder, and wherein said cooperating frictionally engageable parts are located remote from said internal stop in the direction of the cylinder axis.

6. The lock set forth in claim 4 wherein said cooperating frictionally engageable parts comprise a rearward projection on the inner end of

the lock cylinder adapted to travel in an arc during rotation of the lock cylinder, and an inclined cam-like surface on the casing engageable by said projection on the cylinder as the cylinder approaches its locked position of rotation.

7. In a lock of the character described: a casing; a lock cylinder rotatable in the casing between locked and unlocked positions; a rearward extension on the casing projecting beyond the inner end of the lock cylinder; a spring inside said extension reacting between the cylinder and the casing and exerting a torsional force on the cylinder sufficient to effect rotation thereof toward locked position with a snap action; cooperating stops on the inner end of the cylinder and the casing extension engageable with one another to define the locked position of the cylinder; and frictionally engageable surfaces on the inner end of the lock cylinder and said casing extension providing a brake for slowing the rotation of the cylinder under the influence of said spring prior to engagement of said stops.

8. The lock set forth in claim 7 further characterized by the provision of a second set of cooperating stops on the lock cylinder and the casing adjacent to the outer end of the cylinder, said second pair of stops being engageable concomitantly with engagement of the first designated stops.

9. In a lock mechanism of the character described: a lock cylinder; a casing in which the cylinder is rotatably received, said casing and cylinder being relatively axially slidable; cooperating rotation stops on the cylinder and casing defining the locked position of cylinder rotation; a torsion spring acting on the lock cylinder to yieldingly resist rotation thereof out of locked position and for propelling the cylinder to its locked position of rotation from an unlocked position thereof; frictionally engageable surfaces on the cylinder and the casing brought into cooperating relationship as the cylinder is spring propelled toward its locked position of rotation for providing a brake to slow the rotation of the cylinder prior to engagement of said stops, said surfaces producing a camming effect when engaged to produce relative axial motion in one direction between the cylinder and casing; and a recoil spring for yieldingly resisting relative longitudinal motion between the cylinder and casing in said direction, and for assuring good frictional contact between said surfaces on the cylinder and casing.

10. In a lock of the character described: a mounting member having a bore leading rearwardly therein and communicating with a counterbore in line with the bore and opening to the front of said member; a sleeve-like casing in said counterbore; a lock cylinder rotatable in the casing between limits defining the locked and unlocked positions of the cylinder; an operating shaft rotatably received in said bore with its front end disposed adjacent to the rear end of the lock cylinder; a rotation transmitting connection between the cylinder and shaft at said ends thereof, said connection including cooperating parts on the shaft and cylinder for precluding relative axial separating motion therebetween; a connection between the shaft and the mounting member for holding the shaft against forward motion in its bore and consequently for precluding forward displacement of the cylinder from the mounting member; a spline-like connection between the casing and the mounting member precluding rotation of the casing but permitting the

same to slide axially relative to the mounting member and the lock cylinder; a torsion spring connected between the cylinder and the casing for returning the cylinder to the limit of rotation defining the locked position of the cylinder; resilient means reacting between the casing and the mounting member to urge the casing axially forwardly in the counterbore; and stop means on the lock cylinder against which the casing is pressed by said resilient means to preclude forward displacement of the casing from the mounting member, whereby the force of said resilient means is carried through the lock cylinder to said connection between the cylinder and the shaft as well as to the connection between the shaft and the mounting member to maintain pressure on said connections to preclude rattling of the components of the lock mechanism.

11. The lock set forth in claim 10 further characterized by the provision of cooperating cam elements on the cylinder and the casing engageable slightly in advance of return of the cylinder to its locked position to produce rearward sliding motion of the casing against the force of said resilient means acting thereon so that said cam elements and said resilient means cooperate to slow the rotation of the cylinder prior to the cylinder reaching its locked position of rotation.

12. The lock set forth in claim 11 further characterized by the fact that said cam elements are formed as part of cooperating rotation stops on the cylinder and the casing.

13. In a lock of the character described: a casing; a lock cylinder rotatable in the front portion of the casing between locked and unlocked positions; shoulders on the inner end of the lock cylinder and the rear portion of the casing spaced from but facing one another; pilots on the cylinder and casing projecting toward one another from said shoulders coaxial with the cylinder, said pilots having a substantially frusto-conical shape with their small ends adjacent to one another; and a helically wound torsion spring connected between the cylinder and casing for yieldingly resisting rotation of the cylinder out of locked position and for force-

fully rotating the cylinder to locked position from an unlocked position, said torsion spring being received inside the rear portion of the casing between the cylinder and casing shoulders and having its opposite ends substantially closely encircling the large ends of the pilots which lie adjacent to said shoulders whereby the pilots hold the spring against contacting the inside of the casing in consequence to distortion of the spring which results from rotating the lock cylinder in the casing.

14. In a lock of the character described: a sleeve-like casing; a lock cylinder rotatable in the front portion of said casing between locked and unlocked positions; cooperating stops on the cylinder and the casing at the front thereof defining the locked position of cylinder rotation; a helically wound torsion spring axially disposed in the rear portion of the casing and connected between the cylinder and the casing to return the cylinder to its locked position of rotation from an unlocked position; axially spaced pilot means on the rear of the cylinder and on the casing rearwardly and coaxially of the cylinder, and engaged by the end convolutions of the spring to hold said end convolutions coaxial with the cylinder; and cooperating auxiliary stops on the cylinder and the casing adjacent to the rear of the cylinder engageable simultaneously with engagement of said first designated stops to relieve the same of shock incidental to spring propelled rotation of the cylinder to its locked position.

EDWARD N. JACOBI.
